HEAD FOR AN ELECTRIC FLOOR POLISHER OR SIMILAR ARTICLE

Leon P. Borkoski and John T. Ferraris, Stamford, Lurelle
V. A. Guild, Noroton Heights, and John J. Moughty,
Old Greenwich, Conn., assignors to Electrolux Corpora-
tion, Old Greenwich, Conn., a corporation of Dela-
ware

Application April 11, 1958, Serial No. 50,436

Term of patent 14 years

(Cl. D9—2)

FIG 1

FIG 2

FIG 3

FIG 4

FIG 5

Fig. 1 is a perspective view of a head for an electric floor polisher embodying our new design;

Fig. 2 is a top plan view thereof;

Fig. 3 is a front elevational view thereof;

Fig. 4 is a side elevational view thereof; and

Fig. 5 is a rear elevational view thereof.

The side of the head of the floor polisher not shown in the drawings is the same as the side illustrated in Fig. 4.

We claim:

The ornamental design for a head for an electric floor polisher or similar article, as shown and described.
